HYDROXY-PYRIDINE OXIDES IN AN
ANTIFUNGAL METHOD

Jack Bernstein, New Brunswick, James Ling Chen, East Brunswick, and Gilman Norman Cyr, New Brunswick, N.J., assignors, by mesne assignments, to E. R. Squibb & Sons, Inc., New York, N.Y., a corporation of Delaware

No Drawing. Filed Aug. 11, 1965, Ser. No. 479,005
6 Claims. (Cl. 167—58)

This application is a continuation-in-part of a prior application, Serial No. 278,406, filed May 6, 1963, which application is now abandoned.

This invention relates to and has as its objects the provision of new compositions of matter, and more particularly, to new pharmaceutically active compositions useful as topically administrable fungicides.

The new fungicidal composition of this invention comprises essentially a principal active ingredient selected from the group consisting of compounds of the formula

and the non-toxic, pharmaceutically acceptable heavy metal and amine salts thereof, wherein each R is selected from the group consisting of hydrogen and lower alkyl; said principal active ingredient intimately dispersed in a substantial amount of a suitable extending agent.

Preferably, the non-toxic pharmaceutically acceptable salts of the principal ingredient which are employed in the practice of this invention are such heavy metal salts as the zinc salt, and such amine salts as the higher alkylamine salts. By the term "higher alkyl" it is meant an alkyl either straight or branched chain of more than nine carbon atoms and preferably ten to eighteen carbon atoms. These salts may be prepared by reacting the respective principal ingredient compounds with such reactants as zinc oxide or (higher alkyl) amine (e.g., dodecyl amine), respectively.

The compositions of this invention are useful in the topical treatment of dermatophytic fungal infections of animals and may be employed for the treatment or prevention of conditions caused by such microorganisms as *Trichophyton mentagrophytes*, for example, athlete's foot, fungally caused odors, dermatitis, middle ear infections, vaginal infections, ringworm infections caused by *Microsporum canis* and other like fungus infections.

In this disclosure and in the claims appended thereto, the term "dispersed" is used in its widest possible sense. When it is said that the compounds of this invention are dispersed, it means that the particles may be molecular in size and held in true solution in a suitable solvent. It means further, that the particle may be colloidal in size and dispersed through a liquid phase in the form of suspension or emulsions or in the form of particles held in suspension by wetting agents. It also includes particles which are dispersed in a semi-solid viscous carrier such as petrolatum or soap in which they may be actually dissolved in the carrier or held in suspension in the carrier.

The term "dispersed" also means that the particles may be mixed with and spread throughout a solid carrier so that the mixture is in the form of powder or dust. The term "dispersed" also includes mixtures which are suitable for use as aerosols including solutions, suspensions or emulsions of the agents of this invention in a car-

2

rier such as Freon which boils below room temperature at ordinary pressure.

The term "extending agent" as used in this disclosure and in the appended claims, includes any and all of those agents in which the compounds of the instant invention are dispersed. It includes, therefore, the solvents of a true solution, the liquid phase of suspension, emulsions or aerosols, the semi-solid carrier of ointments and pastes and the solid phase of dust and powders.

It has been found that the most satisfactory results are obtained when the active ingredient of this invention is present in an amount of from 0.01% to 10.0% by weight of the final composition, preferably from 0.05% to 5%, and optimally, in an amount of from 0.25% to 5.0% by weight of the final product. This concentration is effective when the dispersing agent is a liquid but it is preferred to use more concentrated mixtures when the dispersing agent is a semi-solid or a solid. This is because liquid dispersions which are of course suitable for use as sprays give a more intimate contact with the area being treated than the solid dispersions and, therefore, lower concentrations are more effective with liquid dispersions.

There are a number of pharmaceutically acceptable solvents which can be utilized for the preparation of solutions, suspensions or emulsions of the compounds of this invention. High boiling oils of vegetable origin such as castor oil, corn oil, sesame oil or olive oil have been found to be suitable. Esters such as isopropyl palmitate or dioctyl sebacate and low boiling, more volatile solvents such as acetone, alcohols, such as methanol and ethanol and the like are also useful. For certain applications it may be advantageous to resort to mixtures of solvents.

If the active agents are to be applied as aerosols, it is convenient to dissolve them in a suitable solvent and to disperse the resulting solution in a liquid such as Freon which boils below room temperature. For such applications it is better to employ true solutions of the active agent although it is possible to employ suspensions or emulsions of the active agent.

The agents of this invention are often dispersed either in the form of emulsions or suspensions, in an inert carrier with the aid of a surface-active substance. Such surface-active substances may be anionic, cationic or non-ionic. There may be mentioned by way of example, natural or synthetic soaps, and the like. Other examples include high molecular weight quaternary ammonium compounds as well as condensation products of ethylene and propylene oxide with monohydric and polyhydric alcohols.

For use as a powder or dust the active ingredient of this invention may be mixed with any of a number of extending agents either organic or inorganic in nature which are suitable for the manufacture of pulverulent preparations. In addition to mixing the ingredients directly the active compounds of this invention may first be dissolved in a suitable solvent and the dry extending agents may be treated with the resulting solution so that after the solvent evaporates off the active ingredient is effectively coated on the surface of the extending agent. The extending agents which may be employed include, for example, tricalcium phosphate, calcium carbonate, kaolin, bole, kieselguhr, talc, calcined magnesia, boric acid and others. Materials of vegetable origin such as powdered cellulose and starch are also useful. These mixtures may be used in the dry form or, by the addition of wetting agents, the dry powder can be rendered wettable by water so as to obtain stable aqueous dispersions suitable for use as sprays.

For special purposes the agents of this invention can be worked into the form of a paste or an ointment by the use of such semi-solid extending agents as soap or

petroleum jelly with or without the aid of solubility promoters and/or dispersing agents.

Generally, the principal active ingredients of this invention may be prepared according to the procedures set forth in U.S. Patent No. 2,540,218, issued Feb. 6, 1951. The compounds wherein R is lower alkyl may be prepared by reacting the appropriately substituted 2-bromopyridine-1-oxides with aqueous sodium hydroxide and recovering the correspondingly substituted 2-hydroxypyridine-1-oxide after acidification of the reaction mixture. Alternately, the appropriately substituted 2-bromo-pyridine-1-oxide may be reacted with sodium benzylate and the 2-benzyloxy-pyridine-1-oxide thus obtained converted to the desired 2-hydroxypyridine-1-oxide by hydrogenolysis in the presence of a catalyst such as palladium on charcoal, or by hydrolysis with aqueous hydrochloric acid.

The zinc salts of these compounds are prepared by treating an aqueous hot solution of the appropriately substituted 2-hydroxypyridine-1-oxide with a warm aqueous suspension of an equivalent quantity of zinc oxide, filtering the hot solution and recovering the zinc salt by lyophilization or concentration of the solution under reduced pressure. The amine salts of these compounds are prepared by adding a warm solution of the appropriately substituted 2-hydroxypyridine-1-oxide in a solvent such as water or an organic solvent such as acetonitrile or a lower alcohol to a solution of the desired amine in water or an organic solvent such as acetonitrile or a lower alcohol filtering the hot solution and cooling to precipitate the salt, which is then recovered by filtration. In those cases in which the salt is soluble in the solvent used, the salt may be recovered by concentration of the solvent under reduced pressure.

The following examples are illustrative of this invention:

Example 1.—2-hydroxypyridine-1-oxide

A solution of 14 g. of 2-bromopyridine-1-oxide hydrochloride in 100 cc. 10% sodium hydroxide is refluxed for two hours. The cooled solution is acidified with concentrated hydrochloric acid and lyophilized to yield 21 g. solid. This dry solid is extracted with boiling hexane to yield 3.6 g. product melting at 144-146°. After recrystallization from 100 cc. hexane the product melts at 148-149°.

Example 2

A solution of 31 g. of 2-benzyloxy-pyridine-1-oxide in 250 cc. abs. alcohol is shaken at room temperature in the presence of 2 g. of 5% palladium on charcoal until the theoretical amount of hydrogen has been absorbed. The catalyst is filtered off and the alcohol removed under reduced pressure. The residue is triturated with cold hexane to yield 12 g. of 2-hydroxypyridine-1-oxide melting at 146-148°. After sublimation at 150-160° and 0.75 mm. the product weighs 10.5 g. and melts at 148-149°.

Example 3.—2-hydroxy-4-methylpyridine-1-oxide

A solution of 12 g. (0.055 M) of 2-benzyloxy-4-methyl-pyridine-1-oxide in 200 cc. absolute alcohol is shaken at room temperature in the presence of 500 mg. of 5% palladium on charcoal until the theoretical amount of hydrogen has been absorbed. The catalyst is filtered off and the alcohol removed under reduced pressure. The residue is triturated with hexane to yield 6.1 g. product melting at 130-132°. The product is purified by sublimation at 80° and 0.3 mm. to yield a white crystalline solid melting at 131-132°.

This compound can also be prepared by refluxing a solution of 22.4 g. 2-brom-4-methylpyridine-1-oxide hydrochloride in 200 cc. 10% sodium hydroxide for two hours. The solution is cooled and acidified with 2% hydrochloric acid to yield the desired product.

Example 4.—2-hydroxy-6-methylpyridine

A solution of 22.4 g. (0.1 M) 2-brom-6-methylpyridine-1-oxide hydrochloride is refluxed for two hours with 10% sodium hydroxide. The solution is cooled and made strongly acid with concentrated hydrochloric acid to yield a crystalline solid melting at 138-141°. After recrystallization from 40 cc. benzene the product is constant melting at 141-142°.

This compound is also prepared by shaking a solution of 2-benzyloxy-6-methyl-pyridine-1-oxide in absolute alcohol in the presence of 5% palladium on charcoal for forty minutes when the theoretical amount of hydrogen is absorbed. The catalyst is filtered off and the alcohol removed under reduced pressure. The crystalline residue is purified by sublimation at 120° and 3 mm. to yield the product melting at 141-142°.

Example 5.—Zinc salt of 2-hydroxypyridine-1-oxide

A solution of 10 g. of 2-hydroxypyridine-1-oxide in 200 cc. water is added to a suspension of 3.7 g. zinc oxide in 400 cc. water. The mixture is heated to boiling and a clear solution formed. This solution is filtered and lyophilized to yield 12 g. product. The solid is triturated with dry ether and dried overnight at 1 mm. to yield the desired product.

Example 6.—2-hydroxypyridine-1-oxide salt with dodecylamine

A hot solution of 7.4 g. 2-hydroxypyridine-1-oxide in 250 cc. acetonitrile is added to a solution of 12.9 g. dodecylamine in 250 cc. acetonitrile. The hot solution is filtered, cooled, and the crystalline solid filtered to yield the desired product melting at 53-54.5°.

Similarly, substituting an equivalent amount of cetyl-dimethylamine for the dodecylamine in Example 3, there is obtained the cetyl-dimethylamine salt of 2-hydroxypyridine-1-oxide.

Example 7.—Preparation of the cetyltrimethyl-ammonium salt of 2-hydroxypyridine-1-oxide

To a solution of cetyltrimethyl-ammonium hydroxide in water (prepared by treatment of an aqueous solution of cetyltrimethyl ammonium bromide with excess silver oxide) there is added an equivalent amount of an aqueous solution of 2-hydroxypyridine-1-oxide. The solution is then lyophilized to recover the desired salt.

Example 8

(A) A composition of the following formula is prepared:

	G.
Zinc salt of 2-hydroxypyridine-1-oxide	1.0
Corn oil	5.0
Ethanol	12.0

The zinc salt of 2-hydroxypyridine-1-oxide is suspended in a solution of the ethanol and corn oil.

(B) The foregoing composition is then introduced into a pressure packaged disperser of known type along with 82 g. of a suitable propellant such as a mixture of fifty parts trichloromonofluoromethane (Freon 11, DuPont) and fifty parts dichlorodifluoromethane (Freon 12, DuPont) or similar propellents either alone or as a mixture. The pressure pack is capped with a suitable valve. Suitable dispersers are disclosed, for example, in U.S. Patent No. 1,892,750 dated January 3, 1933 and in U.S. Patent No. 2,440,915 dated May 4, 1948.

Example 9

(A) A composition of the following formula is prepared:

	G
Dodecylamine salt of 2-hydroxypyridine-1-oxide	0.8
Polyethylene (mol. weight, 21,000)	0.95
Mineral oil	18.05

A polyethylene mineral oil dispersion is prepared as described in Example 1 of U.S. Patent No. 2,628,187, issued February 10, 1953, and the dodecylamine salt of 2-hydroxypyridine-1-oxide is incorporated therein.

Example 10

(A) A composition of the following formula is prepared:

	G.
4-methyl-2-hydroxypyridine-1-oxide	1.0
Powdered talc	99

The 4-methyl-2-hydroxypyridine-1-oxide is added to the powdered talc and intimately mixed therewith.

(B) The foregoing composition may then be separated and packed in shaker type packages for use in the treatment of athlete's foot, as a foot powder.

Example 11

A composition of the following formula is prepared:

	G.
2-hydroxypyridine-1-oxide	2.0
Stearic acid	12.5
Span 60 (sorbitol monostearate)	10.0
Tween 80 (polyoxyalkylenesorbitol monostearate)	6.0
Water	69.5
Perfume oil, q.s.	

This forms a 2% cream.

Heat the stearic acid, Span and Tween mixture to 80°. Dissolve the 2-hydroxypyridine-1-oxide in the water heated to 85° and add to the mixture. Stir until the temperature has dropped to 35° and then add the perfume.

Example 12

A composition of the following formula is prepared:

	G.
2-hydroxypyridine-1-oxide	3.0
Stearic acid	1.4
Triethanolamine	0.6
Glyceryl monostearate	4.0
Lanoline	1.0
Cetyl alcohol	0.4
Mineral oil	2.0
Water	87.5
Perfume oil, q.s.	

This forms a 3% cream lotion.

Heat the water to about 65° C. and add the 2-hydroxypyridine-1-oxide. Add the triethanolamine and warm to 85° C. Melt together the glyceryl monostearate stearic acid, lanolin, cetyl alcohol and mineral oil and heat to 90° C. Incorporate this into the water phase; stir vigorously and continuously until cool. Add the perfume oil when the temperature has dropped to about 45° C.

If a color cream lotion is desired, make a dilute solution of a water-soluble cosmetic color and add along with the perfume oil.

Example 13

A composition of the following formula is prepared.

	G.
Dodecylamine salt of 2-hydroxypyridine-1-oxide	80
Sodium lauryl sulfate	10
Propylene glycol	100
Stearyl alcohol	225
White petrolatum	226
Water	360

This will make an 8% ointment.

Melt the stearyl alcohol and the white petrolatum on a water bath and adjust the temperature to about 75° C. Add the other ingredients previously dissolved in water and warmed to 75° C. Stir the mixture until it congeals.

Example 14

A composition of the following formula is prepared:

	G.
2-hydroxypyridine-1-oxide, zinc salt	50
Cholesterol	30
Stearyl alcohol	30
White wax	70
White petrolatum	820

10 This will make a 5% ointment.
Melt the stearyl alcohol, white wax and white petrolatum together on a water bath. Add the cholesterol until it completely dissolves. Then add the finely powdered zinc salt to the solution, remove from the water bath and stir until the mixture congeals.

Example 15

A composition of the following formula is prepared:

	G.
2-hydroxypyridine-1-oxide, zinc salt	10
Polyethylene glycol 4000	45
Polyethylene glycol 400	35
Sorbitan monopalmitate	1
Water	9

25 This makes a 10% ointment.
Warm the sorbitan monopalmitate and the polyethylene glycols to 70° and add water at 70°. Then add the finely pulverized zinc salt and stir until congealed.

Example 16

A soap is prepared in the following manner.

	G.
Vegetable oil	380
Oleic acid	20
35 Potassium hydroxide	91.7
Glycerin	50
2-hydroxypyridine-1-oxide	30
Distilled water (sufficient to make)	1000 g. of product.

40 Mix the oil and oleic acid and heat to about 80°. Dissolve the potassium hydroxide in a mixture of glycerine and 100 cc. of distilled water, and add the solution while it is still hot, to the hot oil. Stir the mixture vigorously until an emulsion is formed, and heat on a hotplate until the mixture becomes homogeneous and a small portion dissolves completely in hot water. Add sufficient hot water to make total weight about 1000 g., and incorporate the water in soap. Add powdered 2-hydroxypyridine-1-oxide and distribute evenly throughout soap. This makes a "soft" soap, whose properties depend on the vegetable oil used. Oils derived from higher fatty acids and saponified with NaOH will give "hard" soaps.

Example 17

A cream base containing propylene glycol, cetyl alcohol, glyceryl monostearate, spermaceti, isopropyl palmitate, polyoxyethylene sorbitan monostearate, methyl paraben and propyl paraben is prepared in the same manner as set forth in Example 12. A 5% 2-hydroxypyridine-1-oxide cream is prepared from this cream base by the addition of a suitable amount of the active ingredient.

Employing the method of Goss et al., reported in vol. 40 of the Journal of Investigative Dermatology, pp. 299-304 (1963), male albino guinea pigs, weighing 400 to 600 gms. are inoculated cutaneously with *T. mentagrophytes*. Groups of five animals are used, and each animal is infected at three sites, making available fifteen lesion sites for each test formulation. Triamcinolone acetone, 10 mg. is given subcutaneously starting on the day of inoculation and continued daily five days per week for three weeks, then three times weekly for another three weeks. Topical treatment of the test animals with the 2%; 3%; and 5% 2-hydroxypyridine-1-oxide cream; and the cream base as a placebo, was started on the six-

teenth day after infection and continued daily, five days a week. Untreated animals are used as controls. The results are reported below in Table 1:

TABLE 1

(A) Fourteen days post infection, before 2-hydroxypyridine-1-oxide treatment

Test Formulation	No. of inoculation sites	No. sites clear	No. sites infected	Avg. size of lesions (mm. ²)
5% 2-hydroxypyridine-1-oxide cream	15	0	15	382
3% 2-hydroxypyridine-1-oxide cream	15	0	15	343
2% 2-hydroxypyridine-1-oxide cream	15	0	15	416
Placebo cream	15	0	15	396
Untreated	15	0	15	378

(B) Twenty-one days post infection (four treatments with 2-hydroxypyridine-1-oxide starting sixteen days after infection)

Test Formulation	No. of inoculation sites	No. sites clear	No. sites infected	Avg. size of lesions (mm. ²)
5% 2-hydroxypyridine-1-oxide cream	15	0	15	418
3% 2-hydroxypyridine-1-oxide cream	15	0	15	468
2% 2-hydroxypyridine-1-oxide cream	15	0	15	562
Placebo cream	15	0	15	596
Untreated	15	0	15	580

(C) Thirty-two days post infection (ten treatments with 2-hydroxypyridine-1-oxide).

Test Formulation	No. of inoculation sites	No. sites clear	No. sites infected	Avg. size of lesions (mm. ²)
5% 2-hydroxypyridine-1-oxide cream	15	0	15	344
3% 2-hydroxypyridine-1-oxide cream	15	0	15	355
2% 2-hydroxypyridine-1-oxide cream	15	0	15	413
Placebo cream	15	0	15	580
Untreated	15	0	15	446

(D) Fifty-two days post infection (fourteen treatments with 2-hydroxypyridine-1-oxide then sixteen days without treatment)

Test Formulation	No. of inoculation sites	No. sites clear	No. sites infected	Avg. size of lesions (mm. ²)
5% 2-hydroxypyridine-1-oxide cream	15	5	10	-----
3% 2-hydroxypyridine-1-oxide cream	15	12	13	-----
2% 2-hydroxypyridine-1-oxide cream	15	3	12	-----
Placebo cream	15	0	15	(Body completely covered.
Untreated	15	0	15	

¹ These sites represent relapses, since at the end of treatment they were almost clear. The relapses were pinpoint lesions and there was seldom more than one in an original inoculation site, the rest of the area remaining clear.

At sixteen days post-infection, the lesion is uniformly, fully established and measures several square centimeters in area. If left untreated, these lesions will spread to cover the entire skin.

The lesions had attained a considerable size in all three groups of animals, as shown in Table 1, Section A, before treatment. From Sections B and C it is seen that after ten topical treatments with 2-hydroxypyridine-1-oxide cream, there is a marked clearing of the lesions as indicated by their decreased size. The 3% and 5% formulations of 2-hydroxypyridine-1-oxide were equally effective.

When the lesions are examined sixteen days after the last of the fourteen topical treatments, some of the lesion sites treated with 2-hydroxypyridine-1-oxide showed an occasional pinpointed infection, but the remainder of the areas were clear of infection. Animals not treated with this compound were entirely covered with the infection. In other words, the above data indicates that 2-hydroxypyridine-1-oxide controls the spread of the infection at the beginning and thereafter reduces the lesions. This is clearly pointed out by a comparison of Sections A, B and C above. The average size of the lesions treated with 2-hydroxypyridine-1-oxide remain in the three hundred to low four hundred area whereas the lesions treated otherwise spread out of control.

The efficacy of the test formulations is evaluated by comparing, at appropriate time intervals, the appearance and average size (area) of lesions in the treated and untreated animals.

Example 18

Utilizing the procedure set forth in Example 17 except that treatment was started on the animals fourteen days after infection, and the number of animals treated was increased, the results obtained are as indicated in Table 2:

TABLE 2

(A) Seventeen days post infection (ten treatments with 2-hydroxypyridine-1-oxide, then three days without treatment)

Test Formulation	No. of inoculation sites ¹	No. sites clear	No. sites infected	Avg. size of lesions (mm. ²)
3% 2-hydroxypyridine-1-oxide cream	92	84	8	71
Placebo cream	96	0	96	323

(B) Thirty-one days post infection (ten treatments with 2-hydroxypyridine-1-oxide, then seventeen days without treatment)

Test Formulation	No. of inoculation sites ¹	No. sites clear	No. sites infected	Avg. size of lesions (mm. ²)
3% 2-hydroxypyridine-1-oxide cream	86	51	35	74
Placebo cream	90	0	90	225

¹ The figures include the total results from seven separate tests.

² For 78 sites.

The above data indicates the effectiveness of 2-hydroxypyridine-1-oxide.

Example 19

Example 18 was repeated utilizing a cream containing 0.25%, 0.50% and 1% of 2-hydroxypyridine-1-oxide. Five animals injected at three sites were utilized in this example and treatment was stopped on day fourteen. Triamcinolone acetonide was continued to be applied from day fourteen to day twenty-eight. The results obtained are indicated in Table 3:

TABLE 3

(A) Twenty-eight days post infection, fourteen days of treatment

Test Formulation	No. of inoculation sites	No. sites clear	No. sites infected	Avg. size of lesions (mm. ²)
0.25% 2-hydroxypyridine-1-oxide cream	15	0	15	157
0.50% 2-hydroxypyridine-1-oxide cream	15	2	13	101
0.1% 2-hydroxypyridine-1-oxide cream	15	2	13	86
Untreated	15	0	15	239
Placebo cream	15	0	12	225

(B) Forty-two days after infection, fourteen days after treatment stopped but triamcinolone acetonide continued.

Test Formulation	No. of inoculation sites	No. sites clear	No. sites infected	Avg. size of lesions (mm. ²)
0.25% 2-hydroxypyridine-1-oxide cream	15	4	11	155
0.50% 2-hydroxypyridine-1-oxide cream	15	3	12	91
1% 2-hydroxypyridine-1-oxide cream	*12	2	10	61
Untreated	15	0	15	235
Placebo cream	12	0	12	142

¹ One animal died.

Triamcinolone acetonide was given after stopping treatment to continue the infection.

The formulations prepared according to the previous examples can all be topically applied to the animal being treated for the control of *T. mentagrophyte* infections.

The invention may be variously otherwise embodied within the scope of the appended claims.

What is claimed is:

1. A method of treating animals for fungal conditions amenable to topical therapy which comprises topically applying a composition comprising from about 0.01 to

about 10.0% of a principal active ingredient selected from the group consisting of compounds of the formula

and the zinc and higher alkyl amine salts thereof having more than nine carbons; wherein each R is selected from the group consisting of hydrogen and lower alkyl, intimately dispersed in a substantial amount of a suitable topically administrable pharmaceutically acceptable extending agent.

2. A method of treating animals for fungal infections which comprises topically applying a composition comprising from about 0.01 to about 10.0% of 4-methyl-2-hydroxypyridine-1-oxide dispersed in a topically administrable pharmaceutically acceptable powder vehicle, to affected site.

3. A method for treating animals for fungal infections which comprises topically applying an aerosol composi-

tion comprising from about 0.01 to about 10.0% of the zinc salt of 2-hydroxypyridine-1-oxide dispersed in a pharmaceutically acceptable liquid propellant.

4. A method of treating animals for dermatophytic fungal conditions which comprises topically applying a soap comprising from about 0.01 to about 10.0% of 2-hydroxypyridine-1-oxide dispersed in a topically administrable pharmaceutically acceptable soap base.

5. The method of claim 1 wherein the principal active ingredient is the zinc salt of 2-hydroxypyridine-1-oxide.

6. The method of claim 1 wherein the principal ingredient is the dodecylamine salt of 2-hydroxypyridine-1-oxide.
